UNITED STATES PATENT OFFICE.

JOSEF HUTTER, OF NEW YORK, N. Y.

DESIGN FOR A BOTTLE-OPENER.

47,850.

Specification for Design.

Patented Sept. 21, 1915.

Application filed July 7, 1915. Serial No. 38,627. Term of patent 3½ years.

To all whom it may concern:

Be it known that I, JOSEF HUTTER, a subject of the Emperor of Austria-Hungary, residing at New York, in the county of New York and State of New York, have invented a new, original, and ornamental Design for a Bottle-Opener, of which the following is a specification, reference being had to the accompanying drawing, forming part thereof.

The figure is a perspective view of a bottle opener, showing the new design.

The bottle opener comprises in an integral

member a handle extending into two prongs located in one plane therewith. A U-shaped yoke integral with the handle is first bent off this plane, substantially at right angles thereto, and again in a plane about parallel to the first plane. An extension between the legs of the yoke and having a relatively sharp edge is arranged in the plane of the handle.

I claim:

The ornamental design for a bottle opener, as shown and described.

JOSEF HUTTER.
